UNITED STATES PATENT OFFICE.

ROGER G. MARTINDALE, OF CHICAGO, ILLINOIS.

DESIGN FOR AN ADVERTISING GAME-BOARD.

SPECIFICATION forming part of Design No. 21,679, dated July 5, 1892.

Application filed February 11, 1892. Serial No. 421,194. Term of patent 3½ years.

To all whom it may concern:

Be it known that I, ROGER G. MARTINDALE, a citizen of the United States, residing at Chicago, in the county of Cook and State of Illinois, have invented and produced a new and original Design for Advertising Game-Boards, of which the following is a specification, reference being had to the accompanying drawing, forming part thereof, and which represents a face view of my newly-designed advertising game-board.

The leading feature of my design consists in the representation of a checker-board and a map or chart delineating a tract or region of country, with intersecting lines to indicate railroads and their branches and termini, and small circles to indicate stations.

A represents the board, and B the outlines of the squares forming the game-board, which is composed of or divided into sixty-four smaller squares C C', every alternate one of which C' is of a different shade than its ad-

jacentsquare. On the surface of these squares is a map of a section of country with its general characteristic features of mountains, rivers, and lakes, with intersecting lines to indicate railroads and their branches, with stations.

What I claim is—

The design for an advertising game-board herein described, the same comprising the board A, with its beaded or ornamental edge, provided with the ornamental central portion consisting of the outlines B, the checkered diagram composed of the squares C and C', and a map of a section of country provided with lakes, rivers, mountains, cities, towns, and intersecting railways on the surface of the checks, substantially as shown.

ROGER G. MARTINDALE.
